[57] ABSTRACT

The ski safety binding comprises an inserted footplate, held on the upper surface of a ski between two end stops. At least one stop comprises a flexible retaining device. Boot clamping members, of which at least one is adjustable, are provided on the foot-plate so as to permit easy attachment of a boot of shorter length as a boot of longer length than that of the foot-plate. The upper surface of at least one of said stops is substantially flush with the upper surface of the foot-plate to enable one of the ends of a boot longer than the foot-plate to extend beyond it. The upper surface of the end of the foot-plate, which one of the ends of a longer boot can extend beyond, is extended by a small plate. The small plate may be formed in one part with the foot-plate, or fixed in removable manner to the foot-plate.

SKI SAFETY BINDING

The invention relates to a ski safety binding. In particular, it relates to a ski safety binding comprising an inserted foot-plate, held on the upper surface of the ski between two end stops, of which one at least comprises an elastic retaining device, said foot-plate having a pair of footwear fixing means, at least one of which is adjustable, so as to permit the attachment thereto of a boot of shorter length and a boot of longer length than that of the foot-plate with equal facility. The upper surface of at least one of said stops is substantially flush with the upper surface of the foot-plate to enable one of the ends of a boot longer than the plate to extend beyond it.

The advantage of such a safety binding resides essentially in the fact that, upon the fall of a skier or upon an impact involving the risk of causing a strain or a fracture, the foot-plate becomes detached from the ski together with the boot which is attached to it.

The lower surface of the foot-plate can be made very smooth so that, upon the opening of the binding following the fall of a skier or an impact, it does not retard this opening by friction or adhesion to the surface of the ski. The foot-plate can also be formed of a material to which snow only adheres with difficulty and the re-fitting of the ski after the opening of the binding is found to be greatly facilitated thereby.

However, when the boot is of a size greater than the foot-plate and its heel extends beyond the rear edge of the foot-plate, for example, the generally striated sole which constitutes the lower part thereof, retains snow which tends to interfere with the re-fitting of the boot. On the other hand, such a sole of a striated heel generally has a high coefficient of friction, with respect to the upper surface of the rear stop on which it rests, and retards the opening of the safety binding on the fall of a skier or on an impact capable of having serious consequences.

In order to overcome these drawbacks, the binding according to the invention is characterized in that the upper surface of the end of the foot-plate, which one of the ends of a longer boot can overlap, is extended by a small plate.

The accompanying drawing shows, diagrammatically and by way of example, one embodiment of the binding according to the invention.

FIG. 1 is a view thereof in side elevation, partly cut out along the line I—I of FIG. 2.

FIG. 2 is a plan view thereof from above.

The ski safety binding, shown in the drawing, comprises a foot-plate 1 inserted on the ski 2, held by its ends 3, 4 on the upper surface of the ski 2. The rear end 3 of the foot-plate 1 is bevel-edged from above to below in its middle portion, and forms a bevelled tongue 5.

This bevelled tongue 5 is engaged under an edge bevelled from top to bottom of a rear stop 6 fixed to the upper surface of the ski 2. The lateral edges 7 of the tongue 5 are inclined towards one another from front to rear and are in contact having lateral guide rollers 8 with an axis perpendicular to the upper surface of the ski 2.

The edge of the front end 4 of the foot-plate 1 has ramps 9 spreading from a middle hollow area 10, into which the head 24 of a plunger piston 11 extends. The piston 11 is subject to the action of a spring 12, the axis

of which is, parallel to the lateral edges of the ski 2, and forms part of a front stop 13 fixed to the upper surface of the latter. An adjusting screw 14, rotatably mounted axially of the stop 13 at the end opposite the end which carries the plunger piston 11. The adjusting screw serves to compress the spring 12 and to thus increase, in known manner, the force that it exerts on the plunger piston 11.

The foot-plate 1 has on the other hand, in the vicinity 10 of its front end 4, a deformable bow-shaped element 15 into which the front edge of the sole of a boot 16 can be engaged and, in the vicinity of its rear end, a tightener 17 for clamping the upper edge of the heel 18 of the boot 16 against the foot-plate 1 and the front end 15 of the boot 16 against the bow-shaped element 15.

The foot-plate 1 has in its lateral edges, in the neighbourhood of its rear end, holes 19 into which the curved ends of the arms 20 of a stirrup forming part of the tightener 17 can be engaged. It is thus possible to 20 adjust the tightener 17 depending upon the length of the boot 16 to be fixed to the foot-plate 1.

The adjustment of the position of the tightener 17 as shown in FIG. 1, enables the attachment to the foot-plate 1 of a boot 16 whose heel 18 overlaps the rear end 25 of the foot-plate 1 and rests on the rear stop 6, whose upper surface is substantially at the level of the upper surface of the foot plate 1.

In order to prevent the bottom of a portion of the heel 18 of the boot 16 from coming into direct contact with the upper surface of the rear stop 6, a small plate 21, for example of polished stainless steel, is fixed at the rear end 3 of the foot-plate 1, in the same plane as its upper surface, by means of screws 22 engaged in slots 23 of the small plate 21.

The slots 23 enable adjustment of the length of the portion of the small plate 21 extending behind the foot-plate 1, depending upon the length of the part of the bottom of the heel 18 of the boot 16 which overlaps the rear end 3 of the foot-plate 1.

Given that the portion of the bottom of the heel 18 of the boot 16 which is thus applied against the small plate 21 is not in contact with the snow and cannot therefore retain any, it is easy to re-fix a boot rapidly 45 on a ski whose binding is opened in a field of snow. It suffices in fact to engage the rear bevelled tongue 5, of the plate 1 under the bevelled edge of the rear stop 6, then to exert pressure against the head 24 of the plunger piston 11, in order to re-engage in the hollow 50 10 the front portion 4 of the plate 1.

In a modification, there can be provided a mechanism with a lever on the front stop 13, enabling the head 24 of the plunger piston 11 to re-enter the body of this stop 13 by compressing the spring 12, before the 55 replacement of the foot-plate 1 on the ski. It then suffices to allow the head 24 of the plunger piston 11 of the body of the stop 13 to re-emerge in order that it may engage in the hollow 10 of the front portion 4 of the foot-plate 1.

The portion of the sole of the heel 18 of the boot 16, overlapping at the rear of the foot-plate 1 and against which the small plate 21 is applied, cannot brake, on contact with the stop 6, the movements of the foot-plate 1 forward or the lateral movements of the front end 4 of the plate 1, on the opening of the binding, which enables finer adjustment of the latter and confers on it an increased safety of opening.

The small plate 21 can be formed of any material having at the same time a low coefficient of friction with the rear stop 6 and constituting a poor surface for the adhesion of snow. Small plates of synthetic resin or of metal coated with synthetic resin of low coefficient of friction, such as a fluorocarbon resin for example, are extremely well suited.

Instead of a small plate 21 whose overlap at the rear of the foot-plate 1 is adjustable, there may be fixed to the rear of the latter a small plate selected from a set of small plates of variable size. Finally, the small plate 21 can also be formed in one piece with the foot-plate 1.

In bindings with an inserted foot-plate, devised so as to enable the front portion of the sole of the boot to overlap the front end of the foot-plate 1, there may be provided small plates 21 at the front end of the foot-plate 1.

The small plate 21 does not necessarily have to cover the whole surface of the sole overlapping the foot-plate 1. It suffices that its width corresponds to that of the portion of the rear or front stop that it must protect from direct contact with the sole of the boot. Its width can thus be variable with its length.

Small plate 21 may without inconvenience be of greater length than that of the portion of the sole of the boot which overlaps the foot-plate 1, this arrangement enabling the use of a same foot-plate for a large number of boot sizes, which leads to economies of manufacture. In this case, it is advantageous for the small plate to be an elastically deformable strip. In fact, if it were rigid, it could be broken in use with a boot which is too short.

In the case where it would not be possible to find a same material corresponding to all the conditions required for a small plate of large size, such a small plate could be formed by assembling several strips side by side.

The inserted foot-plate provided with a small plate such as has been described constitutes an assembly comprising two functionally different parts. One of these parts, the foot-plate 1, carries the fastenings of the boot and the members cooperating with the stops

mounted on the ski. The other part, the small plate 21, comprises an extension of the first part.

I claim:

1. A ski safety binding for ski boots comprising, a foot-plate for mounting on the upper surface of a ski, spaced front and rear end stops fixed to said ski upper surface and between which said binding is mounted, at least one of said stops including a flexible retaining device, said foot-plate including clamping members for a boot, at least one of said clamping members being adjustable so as to enable the attachment to said ski of a boot of shorter or longer length than the length of said foot-plate, the upper surface of said rear stop disposed substantially flush with the upper surface of said foot-plate to enable one of the ends of a boot longer than the foot-plate to extend beyond it, and a planar extension plate mounted on the rear of said foot-plate and extending the upper surface of the rear end of said foot-plate beyond the rear of said foot-plate and in an overlying manner relative to said rear stop, said extension plate engaging the upper surface of said rear stop and supporting at least a portion of the bottom surface of a heel of a boot to provide a continuous boot supporting member having a substantially planar supporting surface from the toe to the heel of the boot, said extension plate having a low coefficient of friction relative to said rear stop to facilitate separation as an integral unit of said foot-plate extension plate and boot from said ski upon impact of an unusual force.

2. A ski binding according to claim 1, wherein said extension plate is formed in one part with the foot-plate.

3. A ski binding according to claim 1, wherein said extension plate is fixed in removable manner to the foot-plate.

4. A ski binding according to claim 1, wherein said extension plate is connected to the foot-plate in a manner adjustable in the direction of the length of the foot-plate.

5. A ski binding according to claim 1, wherein said extension plate is an elastically deformable strip.
